United States Patent Office

Des. 222,518
Patented Oct. 26, 1971

222,518

FALSE EYELASH APPLICATOR

David C. Brittain, Memphis, Tenn., assignor to Plough, Inc., Memphis, Tenn.

Filed June 29, 1970, Ser. No. 23,728

Term of patent 14 years

Int. Cl. D28—03

U.S. Cl. D86—10

Fig. 1.

Fig. 2.

Fig. 3.

Fig. 5.

Fig. 4.

FIG. 1 is a top plan view of a false eyelash applicator showing my new design;

FIG. 2 is a side elevational view;

FIG. 3 is a bottom plan view;

FIG. 4 is an end elevational view taken from the right hand end of FIG. 3; and

FIG. 5 is an end elevational view taken from the left hand end of FIG. 3.

I claim:

The ornamental design for a false eyelash applicator, as shown.
